CLAIM

The ornamental design for a drawer minibar, as shown and described.

DESCRIPTION

FIG. 1 is a perspective view of my drawer minibar shown with a drawer thereof in a closed position;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of my drawer minibar shown with the drawer in an open position;

FIG. 9 is a top view thereof;

FIG. 10 is a bottom view thereof; and,

FIG. 11 is a left side view thereof.

The broken line showings are included for the purpose of illustrating and form no part of the claimed design.
